SALLY McDougall Henke. INVENTOR.

BY

Carl Miller
ATTORNEY.

UNITED STATES PATENT OFFICE

2,365,817

LADY'S HANDBAG

Sally McDougall Henke, Brooklyn, N. Y.

Application December 18, 1943, Serial No. 514,759

6 Claims. (Cl. 150—29)

This invention relates to a lady's handbag.

An object of this invention is to provide a lady's handbag provided with an inner compartment which closes when the handbag is closed and which opens up when the handbag is opened up. With such construction, articles such as trinkets and the like may be placed in said compartment and they will not mix with other articles placed in the handbag, and even if the handbag were turned over in closed condition, the articles would stay in the compartment.

A further object of this invention is to provide a strong and durable handbag of the character described which shall be relatively inexpensive to manufacture, easy to manipulate and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a perspective view of a handbag embodying the invention with parts broken away and in cross-section;

Fig. 2 is a cross-sectional view taken on line 2—2 of Fig. 1;

Fig. 3 is a view similar to Fig. 2 but showing the handbag opened up;

Fig. 4 is a cross-sectional view taken on line 4—4 of Fig. 3;

Fig. 5 is an end view of the handbag closed up;

Fig. 6 is a partial enlarged cross-sectional view taken on line 6—6 of Fig. 4; and

Fig. 7 is a partial end view taken on line 7—7 of Fig. 4.

Referring now in detail to the drawings, 10 designates a handbag embodying the invention. The same comprises a usual frame 12 comprising a pair of jaws 13 hinged together as at 15. Each of the jaws comprises a top portion 16 and side portions 17. The lower ends of the side portions are connected by the hinge 15. Attached to the frame 12 is a flexible bag body 19 of any suitable construction.

Within the bag is an inner compartment 20. The same comprises a pair of rigid parallel side frame members 21 interconnected by flexible body 22. The longitudinal mid-portion of the body

22 may be stitched to the longitudinal bottom of body 19 as by stitching 24.

The inner compartment further comprises flexible end walls 26 and may also be provided with transverse flexible partitions 27.

Means is provided to suspend the inner compartment 20 from the frame and to open up said inner compartment when the bag is opened up and to close said inner compartment when the bag is closed. To this end there is fixed to each of the side walls 17 of the jaws 13 a spring 30. Each spring 30 has an upper end portion 31 either embedded in or otherwise attached to frame portion 17 in any suitable manner.

Extending from portion 31 of each spring is a portion 32 which extends downwardly and towards the opposite side of the bag. Thus the springs 30 which are attached to the frame jaw 13 on the right side of the bag have downwardly

20 and outwardly extending portions 32 projecting toward the left side of the bag. The lower ends of portions 32 of the springs are hinged to pintles or hinge members 33 attached to the ends of frame portions 21 of the inner compartment.

25 Thus each jaw of the frame 12 is connected to a frame 21 on the opposite side of the inner compartment.

The side frame members 21 are interconnected by interpivoted links as will appear hereinafter.

30 Thus there is attached to the outer side of each side member 21 a hinge 40 carrying a hinge pin 41. There are a pair of hinge members 40 on each frame member 21 and the pairs of hinge plates 40 are aligned. Each pair of pivot pins 41 are interconnected by interpivoted links 42. The links 42 thus serve to keep the frame members aligned so that they will open and close smoothly.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a handbag comprising a frame having interpivoted jaws and a bag body attached to the frame, an inner compartment comprising a pair of parallel side members interconnected by a flexible body, a pair of springs at-

tached to each jaw, means to connect the springs of one jaw to the side member of the inner compartment on the opposite side of said inner compartment whereby opening movement of said jaws will separate said side members to open said inner compartment, and whereby closing movement of said jaws will bring said side members together to also close the inner compartment.

2. In combination, a handbag comprising a frame having interpivoted jaws and a bag body attached to the frame, an inner compartment comprising a pair of parallel side members interconnected by a flexible body, a pair of springs attached to each jaw, means to connect the springs of one jaw to the side member of the inner compartment on the opposite side of said inner compartment whereby opening movement of said jaws will separate said side members to open said inner compartment, whereby closing movement of said jaws will bring said side members together to also close the inner compartment, and a pair of interpivoted links hinged to said side members.

3. In combination, a handbag comprising a frame having interpivoted jaws and a bag body attached to the frame, an inner compartment comprising a pair of parallel side members interconnected by a flexible body, a pair of springs attached to each jaw, means to connect the springs of one jaw to the side member of the inner compartment on the opposite side of said inner compartment whereby opening movement of said jaws will separate said side members to open said inner compartment, whereby closing movement of said jaws will bring said side members together to also close the inner compartment, and a pair of interpivoted links hinged to said side members, the body of said inner compartment being attached to the body of said handbag.

4. A lady's handbag comprising a frame having a pair of interpivoted jaws, a flexible body attached to said frame, an inner compartment within said bag comprising a pair of parallel side members extending longitudinally of the bag, a flexible body interconnecting said side members, a pair of springs having arms fixed to each jaw, and portions extending toward an opposite side of the bag and hinged to a side member at said opposite side of the bag.

5. A lady's handbag comprising a frame having a pair of interpivoted jaws, a flexible body attached to said frame, an inner compartment within said bag comprising a pair of parallel side members extending longitudinally of the bag, a flexible body interconnecting said side members, a pair of springs having arms fixed to each jaw, portions extending toward an opposite side of the bag and hinged to a side member at said opposite side of the bag, and the bottom of the body of the inner compartment being stitched to the bottom of the body of the handbag.

6. A lady's handbag comprising a frame having a pair of interpivoted jaws, a flexible body attached to said frame, an inner compartment within said bag comprising a pair of parallel side members extending longitudinally of the bag, a flexible body interconnecting said side members, a pair of springs having arms fixed to each jaw, portions extending toward an opposite side of the bag and hinged to a side member at said opposite side of the bag, the bottom of the body of the inner compartment being stitched to the bottom of the body of the handbag, a pair of interpivoted members, and means to hinge said interpivoted members to said side members.

SALLY McDougall Henke.
